LEE A. CHRISTY AND GEORGE E. DOLPH, OF DALLAS, TEXAS.

CLAMP FOR CONCRETE FORMS.

Application filed July 5, 1927. Serial No. 203,342.

This invention has for its object to provide an improved device for fastening together panels, boards or the like used in constructing forms or molds where concrete is poured in making pillars, columns, and the like in the construction of concrete and steel buildings. The invention is further applicable to forms or molds of various sorts which require fastening of the parts together to make the form. When applied and used in making forms which require a box-like receptacle in which concrete is to be poured the device enables the work to be considerably expedited, in that the boxing or parts constituting the form can be put together and taken apart in much quicker time than heretofore.

The invention will be clearly understood from a perusal of the following detailed description taken in connection with the accompanying drawings and wherein:

Figure 1 represents a perspective view in part of a form or boxing in which concrete is to be poured and illustrating an embodiment of the device.

Figure 2 is a sectional view along the line 2—2 of Figure 1.

Figure 3 is a side elevational view of the device removed from the form or boxing.

Figure 4 represents a partial top plan view of a form and illustrating a modification of the device; and

Figure 5 is a side elevational view of the modified form shown in Figure 4.

In the construction of buildings of concrete and steel, and to which the device is especially adapted, the forms are fastened together by cross-pieces, that is the cross-pieces are nailed to the panels or boards comprising the box or form into which the concrete is poured. This requires unnecessary time and labor both in the making of the form and removing it.

In carrying out the invention a plurality of cross-pieces 1 preferably 2×4 ft. of required length are fastened together by nails, bolts 2 or otherwise to enable each piece to pivot on the other for free movement in encircling the forms.

The device comprising the invention consists of a piece of steel or other metal 3 flattened on both sides and each end having a substantially squared recess 4. This piece of metal forms a fastening element for secur-

ing the free portions of the 2×4 cross-pieces 55 on which no bolts or nails are used. Since the pieces 1 in position around the form 5 overlap one another the recesses 4 are formed one above the other to enable the body of the cross-pieces 1 to be received.

A particular feature of the invention resides in the construction of the steel or metallic element and wherein the inner edges of the recesses at 6 are made sharp. Thus as shown in Figure 2 after the form is made, 65 the element 3 in place and the concrete poured, the walls of the form, being pushed outwardly by the concrete will cause the sharp edges 6 to bite into the cross-pieces 1 and firmly hold the form together. It will of course be obvious also that the fastening elements 3 may be quickly removed after the concrete has set and is hardened.

A modification of the device is shown in Figures 4 and 5 and wherein the steel fastening element has integrally formed and outwardly projecting ears 7. The ears are perforated for the insertion of screws or nails 8 which are driven into the cross-pieces 1.

What is claimed is:

1. A device for fastening together concrete forms in combination with the cross-pieces of the form, which comprises a flat piece of metal having recesses in each end said recesses adapted to receive the free portions of the cross-pieces surrounding the form to hold said pieces snugly around the form; the inner engaging portions of the metal forming the recesses having sharp edges which when the form is "poured" 90 forces said sharp edges into said cross-pieces constituting a grip.

2. A device for fastening together concrete forms in combination with the cross-pieces of the form, which comprises a flat 95 piece of metal having recesses in each end, said recesses adapted to receive the free portions of the cross-piece surrounding the form to hold said cross-pieces snugly around the form; the edges of the piece of metal adjacent said recesses having projecting ears for reception of elements to attach said pieces of metal to said cross-pieces.

In testimony whereof we affix our signatures.

LEE A. CHRISTY.
GEORGE E. DOLPH.
